HOSIERY DRYING FORM

Application filed December 21, 1929. Serial No. 415,855.

This invention relates to hosiery drying forms and contemplates, particularly, the provision of a form of simple and compact construction which may be advantageously used where it is desired to employ only a single unit.

With the recent improvements in repair needles and the invention of machines for rapidly repairing runs in hosiery, there has grown up a large repair business in conjunction with which the form constituting the subject-matter of the present invention is to be used. Naturally, it is the desire of the repair shop to return stockings to the customer in a neat, pressed condition just as stockings are originally purchased over the retail counter. The advantages of a form such as that which will now be described will therefore be readily appreciated by those skilled in the art.

The principal object of our invention is to provide a hosiery drying form which may be readily heated by simple means and which will remain at a relatively even temperature even though the form be used only intermittently.

Another object of the invention is to provide hosiery drying apparatus comprising a form which is, preferably, rotatably supported upon a pedestal or standard so that stockings boarded thereon may be readily inspected or sprayed, if desired.

A further object of the invention is to provide hosiery drying apparatus including a drying form adapted to contain a heating medium and means located within the form for heating the heating medium therein.

Still another object of the invention is to provide hosiery drying apparatus including a form which may be easily filled with a heating medium and in which the source of supply of the heating medium serves also as an expansion tank for the medium in the form.

Other objects and advantages of the invention will be more fully brought out as the description proceeds.

In the accompanying drawings, we have illustrated a preferred embodiment of our invention and also a modification thereof. It will be understood, however, that these draw-

ings are illustrative, merely, and that our invention is not limited to the details of construction therein disclosed but may, on the other hand, be varied within wide limits without departing from the scope of our invention as defined in the appended claims.

In these drawings:

Fig. 1 is a perspective view of a hosiery drying structure of our invention;

Fig. 2 is a view in section of a portion of the hosiery drying structure illustrated in Fig. 1; and

Fig. 3 is a partial sectional view, similar to Fig. 2, but of a modified form of the invention.

While, as hereinbefore pointed out, it is the essential purpose of the present invention to provide a unitary hosiery drying form which may be conveniently used in the mending service, it will be understood that our invention is not limited to a structure embodying only a single form, but that modifications thereof may include the mounting of a plurality of forms in substantially the same manner herein disclosed.

Referring to these drawings, the reference numeral 1 indicates a hosiery drying form which may be of any suitable and well known construction. The form is provided with an attaching portion 2 which is secured, as by suitable bolts 3, to a hollow base 4. The base 4 is provided with a bearing or projection 5 which extends into a hollow standard 6 supported upon a suitable base or platform 7. This base or platform is preferably made of

considerable weight so as to maintain the structure rigid in upright position and it is also, preferably, sufficiently large so that the operator may stand thereon when boarding stockings on the form. The bearing or projection 5 is rotatable in the standard 6 so that the form may be turned when it is desired to inspect the hosiery or to spray the same. For the purpose of facilitating turning of the form the base piece 4 is provided with a suitable handle 8. Thus, we have provided a compact form of drying apparatus which, broadly, comprises a drying form rotatably mounted on a standard or pedestal.

By referring to Fig. 2, the interior con-

struction of our hosiery drying form will be clearly understood. The interior of the form is divided into two sections or channels by means of a central rib or partition 9 which extends from the base and up into the toe portion of the form. Suitable openings 10 and 11 afford communication between the sections of the form and the interior 12 of the base 4. Projecting into the interior 12 is a baffle 13, the purpose of which is to assure that the heating medium will circulate in the form by passing upwardly through the back of the form into the heel portion thereof and downwardly from the toe portion.

The form is provided with a tube 14 which extends from the toe portion of the form and down through the base 4 and is provided at its outlet end with a suitable valve 15, for a purpose hereinafter more fully pointed out.

A form of the construction so far described is particularly adapted to be used when hot water is employed as the heating medium. In order to fill the form with water, we have provided an expansion tank or reservoir 16 which may be supported by any suitable means at a selected distance above the top of the form. A suitable flexible tube 17 connects the expansion tank or reservoir to the base of the form and through this tube the water will flow from the tank and into the form.

The reference character 18 indicates a heating element for heating the water within the form. Preferably, and as shown in Fig. 2, this is an electric heating element, although it will be readily apparent that any other source of heat might equally well be employed as will be clear from the description, hereinafter, of a modification of our invention. The electric heating element 18 may, of course, be of any suitable and well known construction. Electric energy is conducted to the heating element 18 through suitable conductors 19.

Instead of mounting the heating element 18 in the bottom of the base 4, it may be desirable to employ a so-called immersion heater, that is to say, an electric heater which contacts directly with the medium, such as water, which is to be heated. The advantage of using the so-called immersion type of heater is that the medium is more rapidly heated. However, the heating element is very apt to burn out in the event that the water in the form becomes low and hence it is necessary that the water be maintained at a definite level.

The foregoing description will make clear the construction of our form and it is believed that its operation will also be readily understood by those skilled in the art. The operation may be summarized as follows: Assuming that the form is set up as disclosed in Fig. 1 of the drawings, the first step is to suspend the expansion tank 16 at a suit-

able distance, say one foot, above the toe of the form. The expansion tank is then filled with water which, of course, should be clean and free from foreign matter which might accumulate and become deposited upon the interior of the form. The valve 15 will then be opened and as water flows from the tank 16 into the form the air in the form will be displaced and will pass out through the tube 14. When the form is entirely filled with water, some water will escape through the valve 15 which will then be closed. The form is then ready for operation and the current is turned on to energize the heating element 18. As the water is heated, circulation thereof will be effected through the form, it being understood that the baffle 13 assures that the water will circulate upwardly through the heel portion and downwardly from the toe portion. As is well known, when water is heated, a certain amount of air contained therein is very apt to collect in the toe portion of the form, but this may be overcome by merely opening the valve 15 to allow a small quantity of the liquid to escape. The heating element 18 very quickly heats the water in the form, and since the water will retain its heat for considerable time, it is quite clear that even when the form is used only intermittently it will nevertheless be maintained over such periods at a relatively even temperature.

In Fig. 3 we have disclosed a modification of our invention, the construction of which will now be described. In order to fill the form of this embodiment with water or other heating medium, it is necessary first to remove the form from the standard and fill it with water or other heating medium. The water is introduced into the form through an aperture closed by a suitable plug 22. Thereupon the form is replaced on the standard. A heating means similar to the electric heating element 18, disclosed in connection with the preferred embodiment of our invention, may also be used in the present structure. We have, however, illustrated a different heating means which, in this instance, comprises a gas flame 20, the gas being supplied through a suitable burner 21. It will be understood that as the water, or other medium, is heated in the form, a certain amount of vapor is created and this vapor collects in the toe of the form. There is thus created a pressure which tends to force the heating medium out of the form and into the expansion tank 24 through the pipe 14 and the flexible extension 23. As the form cools, this vapor condenses and thus there is created a vacuum within the form. It will be understood that the expansion tank 24 is open to the atmosphere and consequently atmospheric pressure will force water, or other heating medium, from the expansion tank 24 and into the form, thus maintaining the form filled.

It will thus be seen that we have provided a hosiery drying form which is well adapted for the purposes of the repair business, but the utility of which is by no means confined thereto. Thus, the hosiery drying form of the present invention may also be employed by dyers, who when matching colors, require a small unit for quick drying of samples. While only one form may be required and set up in accordance with the foregoing description, it will be understood, of course, that two or more forms may be similarly mounted, all drawing their supply of heating medium from the same expansion tank.

By the use of our invention, the hosiery mender is enabled to return to his customers the repaired stockings in a condition the same as when new stockings are bought over the retail counter. By the use of hot water as a medium for heating the form, it will be readily appreciated that the form will maintain its even temperature over a much longer period of time so that where the form is used only intermittently, the current for the electric heater may be turned off without materially affecting the temperature of the form itself. Furthermore, the use of hot water enables the operator to maintain a more even temperature and at the degree necessary for the best results.

It is to be noted also that by mounting the form upon a standard, as hereinbefore described, we have provided a simple and satisfactory construction where the usual tables cannot be installed. As has been pointed out, the base 7 is made of heavy material so that the form will remain in upright position, and, furthermore, this base is so large that the operator may stand thereon while boarding hosiery, thus assuring that the form will remain rigid and in upright position.

We claim:

1. Hosiery drying apparatus including a drying form hollow to contain a heating medium, a source of supply of heating medium located above said form, means to convey heating medium from said source of supply to said form, and means unitary with said form for heating said medium.
2. Hosiery drying apparatus including a drying form hollow to contain a heating medium, an expansion tank located above said form and adapted to contain a supply of heating medium, means to convey heating medium from said tank to said form, means to permit escape of air from said form as the heating medium rises therein, and means at the base of said form for heating the heating medium.
3. Hosiery drying apparatus including a drying form hollow to contain a heating medium, an expansion tank located above said form and adapted to contain a supply of heating medium, means to convey heating medium from said tank to said form, means to

heat said heating medium while in said form, and means to promote circulation of said heating medium through said form in a predetermined direction.

In testimony whereof, we affix our signatures.

THOMAS W. PROSSER.
JOHN H. WAHLBECK.
